COLLAPSIBLE SANITARY LINING FOR
WASHBOWLS

Maxwell Eichhorn Lang, New York, N. Y.

Application April 9, 1946, Serial No. 660,815

1 Claim. (Cl. 229—1.5)

1 This invention relates to portable washbowls or to sanitary linings for washbowls.

Heretofore, washbowls made of a simple ply of waterproof paper or the like required the use of frames of wood or the like, to prevent their collapse.

The object of the invention is to provide a sanitary wash basin or washbowl lining which will be self-supporting and provide a close adherence to the standard basins or washbowls on trains, boats, airplanes, etc., and which when not in use may be conveniently packaged for ready transport as a travelling accessory.

The invention contemplates the rigidity obtainable by the reversing of a fold in a sheet of paper or the like, and the invention is particularly applicable to paper of the glassine or cellophane or acetate type, which is waterproof and heatproof and which is relatively stiff though pliable.

For this purpose, the invention consists in a container made of a spherically or ellipsoidally shaped blank of flexible material, pressed into a rather deep bowl having longitudinal bendlines or creases bent inwardly of the outer surface of the bowl, thus having their flattened bites outwardly, such inwardly bent bendlines or creases giving a rigidity to the adjacent body portion of the container or bowl, whereby the bowl is self-supporting when holding a liquid, and does not cause the liquid to be spilled by a partial collapse of any part of the wall of the bowl.

Such a bowl is conveniently shaped by first taking a blank of the desired sheet of material of general square or circular or elliptical shape, and subjecting it to a die action to form a hollow container shape, then folding along longitudinal folds, the lateral portions, and then folding these over each other, along the longitudinal medium line. If desired, the ends may be folded over each other. When desired to be used, unfolding takes place until the bowl shape is obtained, when the preliminary bowl is turned inside out, and the angles of the crease lines smoothed, to lend rigidity to the final shape of the container.

The invention will be more fully described hereinafter, embodiments thereof shown in the drawings, and the invention will be finally pointed out in the claim.

In the accompanying drawings,

Fig. 1 is a perspective view of the improved bowl or liquid receptacle;

Fig. 2 is a plan view of a blank shown in dotted

2

lines with the parts bent over shown in full lines;

Fig. 3 is a section taken on line 3—3 of Fig. 2; Fig. 4 is a plan view of Fig. 2 after the already folded parts are folded longitudinally upon each other;

Fig. 5 is a plan view showing the longitudinal ends overlappingly folded upon each other providing a package ready to be inserted into an envelope when used as a travelling accessory;

Figs. 6 to 12 are diagrammatic views of which

Fig. 6 is a transverse section, as for instance taken on line 3—3 of Fig. 2 with the lateral edge portions folded from full line to dotted line positions;

Fig. 7 is a similar view with the bent over parts in full lines;

Fig. 8 is a similar view with the bent over parts shaped to conform to the body portion outline;

Fig. 9 is a similar view with the overlapping lateral portions moved towards each other to final position, which corresponds to the folded position shown in Fig. 4;

Fig. 10 is a similar view showing how the compacted member shown in Fig. 9 is unfolded;

Fig. 11 shows the same parts when unfolded; and

Fig. 12 shows in full lines the bowl resulting from turning inside out the unfolded position of Fig. 11, the dotted line position corresponding to the contour shown in Fig. 11, the full line position being the up side down position of a transverse section of Fig. 1.

Similar characters of reference indicate corresponding parts throughout the various views.

Referring to the drawings, a flat sheet or blank of suitable shape of glassine paper or cellophane is pressed between two concave-convex die members of spherical or elliptical shape generally resembling the contour as shown in Fig. 1, and this bowl-shaped blank is indicated by 10 in Fig. 2.

The longitudinal axis is preferably larger than the transverse axis. The outer parts 11 of the longitudinal sides are then bent in as shown in Fig. 6 in dotted lines, until the outer parts 11 are folded to the position shown in Fig. 7, the parts 11 having been bent around the hinge or fold lines 12 formed by the bending action. The length of the bent over parts 11 is selected so that their centrally disposed curved free edges almost touch along the longitudinal center line 13 (Figs. 2 and 3), providing diverging contours from the central part outwardly. The parts 11

are then pressed inwardly to contact with the unbent parts 14 of the blank, whereby a concave shape of the parts 11 results, as shown in Fig. 8. Either one of these overlapping parts is then disposed over the other overlapping parts, the hinge or bend being at 13 (Fig. 9). One of the longitudinal ends of this longitudinally folded member (Fig. 4) is then bent over the other longitudinal end, the bend lines being at 16, as shown in Fig. 5, with the ends 17 overlapping. The compact is then ready to be inserted into an envelope (not shown), for commercial distribution.

The importance of this manner of folding is that the bend or hinge portions have angular spaces outwardly disposed with their bites inwardly disposed. For instance, the bite 13a of the hinge 13 faces upwardly in Fig. 3, and the bites 11a formed by the parts 11 and 14 face inwardly, in the preliminary shape of the bowl. However, if the compact shown in Fig. 5 be unbent or unfolded to the position shown in Fig. 10 and then to the position shown in Fig. 11, the use of the same with water as a washbowl would cause it to collapse, and the water would flow out or be spilled. More is necessary to provide a useful article. This results from the recognition of, and making use of the resisting strength obtained from the counter bending of the fold or crease lines. It is necessary to press the angular portions which form the bites 11a and 13a inside out, so as to deflect the angular portions into their opposed positions. This is done by pressing the hinge lines 12 in the direction of the arrows 11c (in Fig. 12) and substantially simultaneously pressing the hinge line 13, in the direction of the arrow 13c, and when this is done, the bowl shaped container 20 is formed, the pressed in angular parts acting to give a permanent shape to the container, so that when inverted from the position shown in full lines in Fig. 12 and into the position shown in Fig. 1, the container or bowl will hold the desired amount of liquid without collapsing.

Thus, the upsetting of the bendlines produced by the creasing or folding of the initial blank, serves to hold the bowl shaped container in a position for use, the upset crease lines largely or seemingly disappearing when they have been evened out by pressure of the hand. The bowl is then provided with an inherent rigidity and stays in the desired position for use and during use. Should the bowl shaped container be desired to be used again at another place, the self-sustaining bowl is inverted to its preliminary position, and the parts are folded in the manner described in connection with Figs. 2 to 9, until the travelling compact of Fig. 5 is obtained.

The advantage of the improved bowl is that it may be either folded to the compact form of Fig. 5, or may be nested in either the preliminary

shape of Fig. 12 of the final shape of Fig. 1, and that it requires no accessory parts of wood or the like to hold it in operative position. It is capable of one or more uses. It provides a sanitary lining to the public wash bowls.

If desired the blank shown in the drawings may be provided with a peripheral margin or band which may be bent over circumferentially so that in the final use of the basin, this brim like band extends substantially at right angles to the downwardly extending basin, and this brim may be placed over the horizontal part of the standard basin in which the improved basin is used as a liner. Generally speaking, the length of the brim would be about one inch. Such a brim is folded upon the face of the blank before the blank is folded as described herein before.

I have described several forms of my invention, but obviously various changes may be made in the details disclosed without departing from the spirit of the invention as set out in the following claim.

I claim:

In a collapsible and convertible bowl in compact transportable flat form, the combination of a crease having its bite extending inwardly of an elliptical bowl shaped blank of glassine like paper, said crease extending along the major axis of the blank dividing the blank into two sides, and a pair of curved creases each having its bite extending inwardly of said blank, and one of said creases being centrally of each side of the blank, forming marginal and inner side portions, said curved creases having their opposite longitudinal ends along the margin of the blank near the longitudinal ends of the major axis crease, the inner surfaces of each marginal and inner side portions being in faying relationship with each other, and the outer surfaces of the marginal side portions being in faying relationship with other, whereby when said flat form is unfolded to bowl shape, and then inverted inside out to form a bowl, said major axis and curved creases have their bites extending outwardly to resist the collapse of the bowl, and to hold the bowl to a smooth interior curved shape.

M. EICHHORN LANG.
